UNITED STATES PATENT OFFICE.

WALTER LARKIN, OF NORRISTOWN, PENNSYLVANIA, ASSIGNOR TO FIDELITY MACHINE COMPANY, OF PHILADELPHIA, PENNSYLVANIA, A CORPORATION OF PENNSYLVANIA.

THREAD-KNOTTING MECHANISM FOR KNITTING MACHINES.

Application filed March 10, 1926. Serial No. 93,726.

This invention relates to mechanism for delivering, to the needles of a knitting machine, a continuous single thread formed of separate lengths of threads of various colors, 5 for the purpose of forming stripes in the fabric being knitted.

The principal object of the invention is to construct the knotting mechanism of the device, in a manner to successfully tie a knot 10 in the adjacent ends of silk threads, hitherto considered impractical.

It will be understood that the device is capable of selecting the desired thread from a series of different threads maintained in a 15 given position by the device, tying it to the running thread while the knitting machine is in operation, cutting the running thread adjacent the knot and returning it to its normal inactive position, the selecting and 20 tying of the threads being controlled by pattern mechanism operable by the driving mechanism of the knitting machine.

Other advantages and the detailed construction of the invention will be fully disclosed hereinafter, being clearly illustrated 25 in the accompanying drawings, of which:

Fig. 1 is a front elevation showing my invention as applied to a circular knitting machine;

Fig. 2 is a side elevation of the apparatus shown in Fig. 1;

Fig. 3 is a front elevation on a larger scale than Figs. 1 and 2 illustrating in their normal positions the main parts of the attachment constituting my invention;

Fig. 4 is a side elevation of the mechanism shown in Fig. 3, a portion of the frame being broken away;

Fig. 5 is a plan view illustrating the knotting device and certain of its associated mechanism;

Fig. 6 is a front elevation of the parts shown in Fig. 5;

Fig. 7 is a plan view of the knotter detached from the machine;

Fig. 8 is a front elevation of the knotter as shown in Fig. 7;

Fig. 9 is a plan view of the knotter with the cover plate removed;

Fig. 10 is a longitudinal vertical section of the knotter taken along the line 10, 10, Fig. 7;

Figs. 11 and 12 are diagrammatic plan

and elevational views respectively of the knitting head and the knotter shaft; 55

Figs. 13 and 14 are respectively a front and side elevation illustrating an active position of certain of the elements of my invention, at the beginning of the knotting operation; 60

Figs. 15 and 16 are views similar to Figs. 13 and 14 respectively showing the elements in an intermediate active position during the knotting operation;

Figs. 17 to 25 inclusive are perspective 65 views illustrating the actual knot tying operation; and

Figs. 26 and 27 are sectional views taken on the line 2, 2 of Fig. 25 illustrating the method of snubbing the threads to be tied. 70

In Figs. 1 and 2 of the above drawings, 1 represents a portion of the frame of a well known form of circular knitting machine, which in the case illustrated, is of the dogless dial type, described and claimed in my 75 U. S. Patent No. 1,433,384, dated October 24, 1922. The upper part of said frame 1 carries a circular bed plate 2 providing a bearing for a rotary cam ring 3 and supports a stationary needle cylinder 4. Said 80 bed plate also carries posts 5 supporting a yoke 6 which serves to carry and hold from rotation a dial post 7, on whose lower end is mounted the dial of the knitting machine. The cylinder cam ring 3 likewise carries a 85 pair of posts 8 supporting a yoke 9 which serves to support and drive a dial cam ring 10.

The cam ring 3 is driven through gearing (not shown) mounted within a closed 90 casing 11 and driving a horizontal shaft 12 journaled in bearings in the frame 1. This shaft has fixed to its free end a cylindrical enlargement 13 whose outer face has a crank pin 14 on which is mounted a pawl 15, for 95 engaging and intermittently turning a pattern wheel 16 which governs the operation of the knitting machine. The frame 1 has fastened to it a bracket providing a bearing 17 for a countershaft 18, which has fixed to 100 its outer end a sprocket wheel 19, in the present instance having its teeth formed with two series of radial notches 20 for the reception of the two runs of a pattern chain 21 whereby the operation of my invention is 105 controlled. The shaft 18 also carries a

ratchet wheel 22 engaged by a hooked pawl 23 forming part of or attached to the strap 24 of an eccentric 25 on the driven shaft 12. The rotation of this shaft through the pawl 23 and ratchet wheel 22, intermittently turns the sprocket wheel 19 and the pattern chain 21 thereon.

That portion of the frame 1 on which the pattern wheel 16 is mounted, has pivoted to 10 it a selector lever 26 which includes an arm carrying a roller 27 (Fig. 2) positioned to be engaged by certain high links of the pattern chain 21. Said chain includes in the present case four sets of these links indicated 15 at 21^a, 21^b, 21^c and 21^d, of varying heights or degrees of projection, so that as they are brought under the roller 27 by the rotation of the sprocket wheel 19, the lever 26 is turned on its pivot or fulcrum 28 through 20 corresponding angles. The free end of this lever 26, through a link 29, is connected to one arm of a bell crank lever 30 acted on by a spring 31 to at all times draw said lever 26 and hence its roller 27, toward the pattern 25 chain 21.

As shown in Figs. 1 and 2, the machine has a bracket or plate 32 projecting horizontally for the support of a vertically extending post 33 on which is mounted a casing 34 containing part of the stop motion mechanism. Said bracket also carries a vertically extending rod 35 projecting considerably above the top of the machine and carrying at its upper end a second casing 36 in 35 which is pivoted one end of a projecting yarn guiding finger 37. This latter also forms part of the stop mechanism of the machine and actuates said mechanism when drawn downwardly beyond a predetermined 40 point. The mechanism in the casing 34 is controlled by a movable arm having a series of parallel fingers 39 positioned to coact with a stationary grid 40, the arrangement being such that fingers and grid are maintained 45 substantially parallel and immediately adjacent each other under operating conditions by the length of yarn passing between them and running through the eye carried by the finger 37 down to the knitting mechanism. 50 In the event of breakage of the yarn the arm with the fingers 39 is released and its fall from the position shown causes operation of the stop motion.

In accordance with my invention, I utilize 55 the lower portions of the posts or rods 33 and 35 to support a frame 41 which may be held thereto in any desired or suitable manner and to which is fulcrumed the bell crank lever 30. For this purpose, I rotatably 60 mount in said frame a spindle 42 on which said lever is journaled. This spindle within the frame also has mounted upon it a beveled gear 43 whose teeth mesh with those of a beveled pinion 45 formed integral with a 65 sleeve 45^a rotatably mounted on a fixed spin-

dle 46, (Fig. 6) whose inner end is fixed in any suitable manner to and carried by the frame 41. The outer end of the sleeve 45^a has formed integral with it a radially projecting arm 47 serving to support a yarn carrier which has the form of a segment 44 concentric with respect to the sleeve 45^a. The face of the segment 44, adjacent its forward or advance end, is in the form of a groove cut back on an angle from its outer periphery to the base thereof, to form a wide throat for receiving a selected thread and carrying it forward and upward, for purposes hereinafter set forth.

To the rear of and parallel with the shaft 80 42, the frame 41 carries a fixed rod 48 (Figs. 5 and 6) on which are pivoted any desired number, in the present instance four, yarn guide fingers 49, 50, 51 and 52. Each of these consists of an elongated bar extending 85 downwardly and forwardly from the rod 48 and having its lower end curved forwardly and upwardly, each bar being perforated adjacent its extremity for the reception of one of a number of yarns to be delivered to 90 the knitting machine. These yarn guide fingers are at all times pressed upwardly toward a normal position in which they engage a cross bar 53 by springs 54 preferably coiled on a rod 55 supported at the rear of 95 the frame 41. Any one of said fingers may be depressed from its normal elevated position to a lowered position by a selector 56 which is rotatably as well as longitudinally movable on the spindle 42 and which has a 100 width slightly less than that of any one of the various fingers.

For rotating this selector, the beveled gear 43 has fixed in and projecting laterally from it a pin 57 which extends through a suitable opening in said selector so that the latter is necessarily rotated with said gear regardless of its distance from the same or of its position upon the shaft 42. Said selector has a projecting hub 58 formed with an annular 105 recess for the reception of an arm 59, fixed on a selector rod 60 slidably guided in portions of the frame 41. One end of this rod has a projecting pin 61 operative in a slot 62 formed in the selector cam 63 which is fixed 110 to and moves with the bell crank lever 30. 115

With this arrangement of parts, the swinging of said lever 30 on the shaft 42 moves the selector cam 63 concentrically with said shaft and causes the wall of the cam slot 62 to co-operate with the pin 61 to move the selector rod 60 longitudinally to an extent dependent upon the arc of movement of said bell crank lever. The parts are so arranged that when the pin 61 is in its 125 normal position at the lower end of the cam groove 62, the selector rod 60 with the arm 59 holds the selector 56 in a vertical plane including the extreme right hand yarn guiding finger 49. If now the gear 43 be turned, 130

the consequent rotation of said selector by the pin 57 will cause this particular yarn guiding finger to be depressed. Obviously, by varying the arc of movement of the bell 5 crank lever 30, the selector cam 63 may be caused to act on the selector 56 to position it in the plane of any one of the other yarn guides 50, 51 and 52. As previously noted the bell crank lever 30 is actuated through 10 the lever 26 and the bar 29 from the different high links of the pattern chain 21.

Immediately above the sleeve 45^a of the beveled pinion 45 I mount the knotting and shearing device 64 which comprises a casing 15 164 suitably secured on the frame 41. Suitably secured within the casing 164 is a bearing block 165 provided with a vertically disposed cylindrical opening 166 adapted to receive an operating spindle 167.

20 Disposed horizontally and at right angles to the opening 166 and at either side thereof is a bearing aperture 168 and 169. The bearing opening 168 is suitably bushed as at 170 for the reception of a rotatable knot 25 tying spindle 171. Rotatably mounted within the bearing opening 169 is the hub 172 of an eccentric ring 173. Intermediate the hub 172 and eccentric ring 173 and integrally formed therewith is a gear wheel 174 30 adapted to a counterbored opening 175 in the bearing block 165. The outside face of the gear 174 lies in a plane flush with the face of the bearing block, wherein a retaining screw 176 is positioned in a manner 35 whereby its head overhangs the opening 175 and the gear 174, thereby retaining the said hub 172, eccentric ring 173 and gear 174 within the said bearing block. The ring 173 is apertured at 177 to provide clearance for 40 the head of the screw 176 when the ring is rotated.

The teeth of the gear wheel 174 mesh with the teeth 178 formed on a plate gear 179 which is secured to a flange 180 integrally 45 formed on the operating spindle 167 of the knotting and shearing device.

The plate gear 179 is provided with a second series of teeth 181 adapted to engage a series of gear teeth 182 formed on one end 50 of the knot tying spindle 171. The opposite end of the knot tying spindle 171 extends through an axially aligned opening formed in the hub 172 of the eccentric ring 173, whereby a bearing for this end of the 55 spindle 171 is provided.

The spindle 167 is provided with an aperture 183 of sufficient diameter to permit the passage of the spindle 171 therethrough and also to permit a relative oscillation of the 60 spindle 167 around the spindle 171. The spindle 171 is provided with an annular groove 184 in axial alignment with the centre of rotation of the spindle 167 for the reception of a reduced plain end of a retaining screw 185 which is axially aligned

with a second screw 186 threaded into and axially aligned with the spindle 167, from the opposite end thereof.

The end of spindle 171 adjacent the eccentric ring 173 is provided with a hooked end 187 which forms a fixed element of a snubbing clamp which is adapted to grip the adjacent ends of the lengths of thread which are to be tied together. A second fixed element in the form of a thin plate 70 188 is positioned adjacent the hook 187 and is of a similar outline thereto, while a third fixed element 189 of similar outline is provided to function as a fixed shear blade, one edge thereof being beveled for that purpose. 80

Positioned intermediate the fixed elements 187, 188 and 189 and pivoted thereto at 190 is a pair of cooperating movable elements 191 and 192. The movable element 191 lies between the fixed elements 187 and 188 and is adapted to snub the threads in a manner 85 illustrated in Fig. 27. The movable element 192 lies between the fixed elements 188 and 190 and co-operatively functions with the fixed shear blade 189 to shear the ends 90 of the threads being knotted.

The movable elements 191 and 192 are each provided with a broad fan like end 95 193, opposite its hooked end, which is located within the eccentric ring 173 and in co-operation therewith functions to operate the movable snubbing and shearing elements 191 and 192 in a manner hereinafter set forth.

The casing 164 is shouldered at 194 for the reception of a cover plate 195 which 100 is frictionally secured in place by means of a pair of clamp screws 196, 196, tapped into the vertical wall of said casing.

Secured to the under side of the cover plate 195 is a cam 197 adapted to receive 105 a cam roller 198 rotatably mounted on a pin secured in one end of a slidble clamp blade 199. The blade 199 is adapted to slide longitudinally between a pair of blades 200, 200 which lies above and below the blade 199. The blades 200, 200 are apertured to receive the vertical spindle 167 and fit within an opening 201 in a flange 202 on the upper surface of the plate gear 179 for the purpose of co-operative oscillation with 110 said plate gear. 115

The blade 199 is likewise adapted to oscillate with the plate gear 179 and clamp blades 200, 200 and in addition thereto to receive a longitudinal movement relative to said 120 blades, a slot 203 being provided thereon to permit such movement around the spindle 167.

The blades or figures 199 and 200, 200 are provided with notches 204 and 205 respectively and the walls of said slots are adapted to co-operatively engage the threads being tied, as will be more fully described herein-after. The fingers are adapted to pass over the knotting, snubbing and shearing blades 130

and move in a horizontal plane thereabove from one side to the other of said knotting blades.

The movable elements of the snubbing clamp and the clamp blades are actuated by the spindle 167 which extends vertically through the knotter and has fixed to its upper end an operating arm 68. For oscillating the arm 68 to operate the knotting and cutting blades, I provide a pin 70 projecting from said arm and engaged by one end of an arm 71 (Figs. 4 and 5) whose opposite end is fixed to a vertical spindle 72 journaled in suitable bearings in the frame 41. This vertical spindle has fixed to its lower portion a pair of arms 73 and 73^a carrying replaceable shoes which project toward the cylinder cam ring 3.

For the purpose of periodically actuating this arm 73 and hence the tying, snubbing and cutting hooked blades 187-192, and the gripping blades 199 and 200, I mount on the cylinder cam ring 3 or other rotary part of the machine in timed relation with said ring, a cam 74 (Figs. 11 and 12) and while this cam would ordinarily engage the arm 73 at each revolution of the cylinder, I prevent such engagement except when desired by making the spindle 72 vertically slidable in its bearings so that said arm is normally held at a level above that of said cam 74. For this purpose, I fix to said spindle 72 a third arm 75 which rests on the selector pin 57, and make the under face of said arm substantially horizontal or parallel with the pin 57, so that it engages with the selector pin regardless of its position relatively to the yarn guiding fingers 49, etc. Normally said selector pin holds the arm 75 and with it the arm 73 in a raised position so that the latter can not be engaged by the cam 74 on the cylinder cam ring. When however, the selector 56 is rotated to depress one of the yarn guiding fingers 49-52, said arm 73 is likewise lowered and it may be engaged by the cam 74 so that the spindle 72 will be turned to operate the knotting device at the next rotation of the said cylinder cam ring.

In order to return the elements of the knotter to their normal positions the arm 73^a is engaged by a cam 74^a secured to the cam ring 3, at a point diametrically opposite the cam 74, the cam 74^a engaging the arm 73^a and moving the spindle 72 in an opposite direction.

For actuating the beveled gear 43 and its associated parts at such times only as their action is desired, I fix to the driving shaft 12 an eccentric 76 having mounted thereon a strap connected through a rod 77 with a lever arm 78 on a spindle 79 carried by the bracket 32. Said lever includes an arm 77^a and a tooth 80, designed to be engaged by a spring actuated pawl 81 pivoted to a second lever 82 on the spindle 79, so as to transmit mo-

tion from said first lever 78 to said second lever. The latter includes also an arm in which a set screw 82^a is adjustably mounted in position to be engaged by the arm 77^a to positively move the lever 82 in a direction opposite to that in which it is moved through the pawl 81. A controller cam 83 connected to a third lever 84, also rotatably carried by the spindle 79, normally holds the pawl 81 in such a raised position that the oscillation of the lever 78 by the rod 77 can not affect it or the lever 82. This third lever through a link 85, is connected to the bell crank lever 30, and the arrangement is such that when the latter is turned from its normal position by any one of the high links of the pattern chain 21, the controller cam 83 is thereby turned into a position to permit the pawl 81 moving into engagement with the tooth 80, thus causing the arm 82 to be moved at the next forward movement of the lever arm. The arm 82 through a link 86, is connected to a pin 87 on the beveled gear 43 so that the latter may be turned by said arm through such an arc as will cause turning of the pinion 45 and of the segment 44 through an angle of somewhat more than 180°.

For holding the ends of any three of the yarns *w*, *x*, *y*, and *z* while the fourth is being delivered to the knitting machine, I provide a flat segmental shield 88 mounted on a block 89 held by a screw 90 to the fixed stud 46 on which is carried the sleeve 45^a. The curved periphery of this shield is concentric with the carrier segment 44 and on the left side of its center it has fixed to its front face a second block 91 on the front of which a pair of superposed angular guide plates 92 and 93 is held by suitable means such as the screws 94. The inner one of these two plates has a downwardly curved guide lip 95 at whose inner end is a yarn receiving recess 96 and its top otherwise flat face is grooved or serrated to facilitate holding the yarn or thread thereto.

The outer guide plate 92 has a second yarn guiding lip 97 extending horizontally over and substantially parallel with the lip 95 and the inner edge of said plate is toothed or notched as indicated at 98 to assist in holding the several yarn ends from movement as hereinafter described. In addition I provide this plate with a notch or recess 98^a for holding and guiding a thread at certain times during operation of my invention.

Above and spaced away from the top of the lip 97 is a forked or notched guide plate 99 projecting upwardly at an acute angle to 125 the horizontal and held in position by a screw 100. The notch of this third guide plate and the recesses 96 and 98^a of the two members 93 and 92 are arranged one above the other and all above the top and inner 130

edge of a guard plate 101 held in place by the screws 94 and projecting in front of the lower right hand portion of the shield 88. The upper edge of this shield plate is bent 5 inwardly to form a guide finger 102 for purposes hereinafter set forth.

Immediately above the flat face of the block 91 and under the horizontal top of the angle plate 93 is a temporary yarn holder 103 in the form of a flat plate pivotally mounted on a screw 104 set in the block 91 and having its free end distant from said screw inclined. A spring 105 mounted on said screw 104 is operative on this holder 10 to force its inclined end toward the adjacent 15 flat face of the shield 88, so that one or more ends of yarn extending vertically between the shield and guard plate and upwardly through the recesses 96 and 98 at the inner 20 ends of the guide lips 95 and 97, will be gripped and temporarily held from dropping down.

For frictionally holding the ends of the 25 yarns not being fed, I connect to the lower end of the spindle 167 of the knotter 64 a laterally projecting hooked arm 106 (Fig. 6) having one edge serrated and designed to operate between the horizontal portions of the angle plates 93 and 92 and to frictionally 30 coact with the roughened top face of the former to tightly grip and normally hold from movement the yarn ends engaged therebetween. This arm 106 operates in 35 timed relation with the blades of the knotter being designed to move toward the free 40 ends of the lips 95 and 97 and after the tying of a knot and the severing of the lengths of yarn, to quickly return to a position frictionally gripping the yarn ends 45 against the roughened top face of the plate 93. A plain arm 106^a, similar in outline to the arm 106 but having a straight edge rather than a toothed edge, is secured to the spindle 167 adjacent the arm 106 and there- 50 above, its outer end lying on the top surface of the yarn holder 103 for a purpose hereinafter set forth.

With the above described arrangement of parts, I preferably extend the rod 33 downwardly below the bracket 32 and mount thereon any suitable form of holder or carrier for a plurality of bobbins or spools of yarn, of which there are four in the machine illustrated. From said bobbins, four yarns 55 *w, x, y, z*, lead respectively through suitable openings in the arms of a yarn guiding spider 112 mounted on the post 33, from whence they pass to the eyes of the yarn guiding fingers 49, 50, 51 and 52. From the 60 first of these fingers the yarn *w*, for example, normally passes upwardly over the rear face of the shield 88, thence through an opening in a guide plate 111, between the grid 40 and finger 39, through the eye of the stop- 65 motion yarn sweep 37 and down to the knit-

ting machine proper. There is thus formed between the elements 39-40 and the knitting machine cylinder an elongated loop of yarn which may be shortened or elongated, by reason of the ability of the finger 37 to 70 swing vertically.

The ends of the three other yarns *x, y, z*, pass between the shield 88 and the relatively narrow neck portion 101^a of the guide plate 101, thence between the upper part of the 75 shield 88 and the inner edge of the spring-actuated holding finger 103, through the notch 96 of the angle plate 93 and are gripped between the roughened top surface of the latter and the hooked arm 106 which 80 projects from the spindle 167 of the knotting device.

The several parts of the machine now occupy the relative positions illustrated in Figs. 3 and 4, so that the knitting machine 85 will knit ribbed fabric from the yarn *w*, which, for example, may be blue. If it be assumed that the next to the lowest of the elevated links 21^b of the pattern chain 21 is brought, by the intermittent turning of the 90 sprocket wheel 19, into engagement with the roller 27, then the lever 26 is swung on its supporting stud 28 through an angle depending on the height of said link, thus through the rod 29 turning the lever 30 to 95 a corresponding extent. This movement of said lever, through the link 85 swings the controller cam 83 in a counter clockwise direction so that the pawl 81 under the action of its spring is moved in front of the tooth 100 80 (Fig. 4), as this is drawn to the rear by the action of the eccentric 76 transmitted through the rod 77. At the same time, the above movement of the lever 30 with its selector cam 63 causes the pin 61 to be moved 105 into a position adjacent the lower part of the cam groove 62, with the result that the rod 60 is moved longitudinally toward the left, carrying with it the selector arm 59 and moving the selector 56 into a vertical plane 110 including the yarn guiding finger 50. It will be understood that prior to the above described action and throughout the entire operation of my attachment as subsequently set forth, the knitting machine is in full 115 operation, so that the shaft 12 is continuously turned and with it the eccentric 76 thereon. This eccentric is so set that after the rearward movement of the controller cam 83 above described, said eccentric moves 120 outwardly the bar 77 and with it the tooth 80 so that through the pawl 81 the arm 82 is swung upwardly thus raising the link 86. Such upward movement of said link turns the beveled gear 43 and with it the selector 125 56 in such a direction as to turn the pinion 45 and carrier ring segment 44 in a counter clockwise direction, at the same time dropping the arm 75.

The turning of the selector 56 depresses 130

the yarn guiding finger 50 into the position indicated in Figs. 13 and 14, in which the yarn end α passing therethrough is drawn down so that the portion thereof leading from said finger lies directly in the path of the angular end of the carrier segment 44, shortly after this begins its movement from the normal position shown in Fig. 3. As before noted, the yarn w which is being fed 10 to the knitting machine, runs from its guide 49 backwardly and upwardly to the lower edge of the shield 88, so that as the yarn α is carried by the segment 44 into the position shown in Figs. 13 and 14, it crosses and 15 engages said yarn w drawing it to the right toward and finally off of point of the right hand end of said shield. The tension of the 20 yarn w causes it thereafter to pass in a straight line upwardly between the shield 88 and the guard 101 (Figs. 15 and 16).

In the meantime, the continued rotation 25 of the carrier segment 44 draws the yarn α from its bobbin and lays it in the groove of said segment as the recessed end 44^a thereof swings the end portion of said yarn about 30 its held extremity as a center, until finally the yarn w immediately below the knot catcher plate 111, is also engaged and caused to enter said recess 44^a of the carrier segment. The two runs of yarn w and α are 35 now carried together from the positions indicated in Figs. 13 and 14 to the position shown in Figs. 15 and 16 back of the lips or tongues 95 and 97 into the recesses 96 and 398^a and also against the face 99^a of the guide 99 being drawn to the left into the angle of and over the hooks 187, 188 and 189 of the 40 knotter, the point 102 of the plate 101 acting to guide the said threads positively into such position. During the above described movement of the two yarns the yarn w runs between the shield 88 and the guard plate 101 and the yarn α is carried to the back face 45 of the shield 88 and as the segment 44 continues to move toward the left over the top, the yarn α hangs down from the rear edge 44^b thereof and is engaged by a point 195^a protruding, from the plate 195 of the knotter 64, into the path of the yarn, to absorb any 50 slack which may be in the yarn due to the rotation of the said segment past the horizontal plane of its centre of rotation.

As the machine continues to operate, the 55 cam 74 carried by the cylinder cam ring comes into engagement with the arm 73, which has been dropped into its horizontal plane of movement by the lowering of the arm 75 by the selector pin 57 so that said arm 73 with the vertical shaft 72 is turned, 60 thereby swinging the arm 71 and through the arm 68, turning the central spindle 167 of the knotting and cutting device 64 in a counter clockwise direction as viewed from above. This causes the yarn gripping fingers 65 199—200 to move toward the parallel yarns

w and α (Fig. 17) which are so positioned that they enter the notches 204 and 205 in said fingers. At the same time the snubbing, knotting and shearing blades 187—192 begin to rotate in a counter clockwise direction 70 (Fig. 18) and in view of their angular form and inclined setting relative to the two lengths of yarn, their extremities move across the latter forming them into a loop around the necks of said blades, (Figs. 19 75 and 20) by the time they have completed a half revolution. During the continued rotation of said knotting blades, the fingers 199 and 200 with the hooked plate 106 continue to swing toward the right and as the points 80 of the blades 187—192 swing upwardly from the positions shown in Fig. 20 to that shown in Fig. 21, the holding finger 199 moves radially inward parallel with the finger 200, gripping the two lengths of yarn in the 85 notch 204—205.

The angular and radial movement of the fingers 199 and 200 and the rotational movement of the blades 187—192 is under the direct control of the spindle 167 and plate 90 gear 179, which also controls the eccentric ring 173, rotating it in a direction opposite to that of the spindle 171 for the purpose of accelerating the opening and closing movements of the movable blades 191 and 192. 95

It will be understood that the above described rotation of the knotter blades stops the feed of the yarn w momentarily, but none the less the knitting machine continues to operate, since it takes up the yarn in the long loop between the falling finger 39 and the 100 needle cylinder, the sweep arm 37 gradually swinging down as the loop is decreased in size by reason of the yarn being drawn into the machine. 105

As the hooked arm 106 swings to the right its forward curved edge slides past the two threads w and α which being in the recesses 96 and 98 are held by the walls thereof from likewise being drawn out of position toward the right. During the upward turning of the knotter blades, their ends separate or open so that by the time they have moved into the substantially horizontal position shown in Fig. 21, the double run of the two 110 yarns w and α enters between the fixed blades 187, 188 and 189 and the two movable blades 191 and 192 being properly positioned for this purpose by the innermost point of the edge 99^a of the element 99. 115 The continued movement of the holding fingers 199 and 200 toward the right causes the loop of yarn around the knotting blades to be drawn from their necks toward their points, Fig. 22, which gradually move together until just after the fixed blades 187, 188 and the movable blades 191 frictionally grip or snub the yarns thereby securely holding the yarn against slipping, the blades 189 and 192 finally sever them as shown in Fig. 120 125 130

23. While the severed ends adjacent the loop in the yarn are thus frictionally held the continued movement to the right of the holding fingers 199 and 200 draws said loop off of said blades, thus forming and pulling 5 tight a knot as indicated in Fig. 24. After the completion of the knot, the continued rotation, in opposite directions, of the spindle 171 and the eccentric ring 173 co- 10 operate to open the blades 187—192 to release the tied yarns immediately and also to move the finger 199 outwardly to release the yarns from the co-operating notches 204, 205 in the fingers 199 and 200.

15 In the meantime, the other pair of severed 15 yarn ends as well as the ends *y* and *z* are frictionally held between the finger 103 and the adjacent face of the shield 88, while the hooked arm 106 is moved into the position 20 at the extreme right side and beyond the severed yarn ends. The high link of the chain 21 moves from under the roller 27 of the arm 26 and the bell crank lever 30 with the selector cam 63 are returned to their normal 25 position. The segment 44 and the selector 25 56 are likewise returned to their normal positions, thereby raising the spindle 72 and arm 75^a thereon into a position to be engaged by the cam 74^a whereby the elements 30 of the knotter are forcibly moved to the left and into their normal positions. With them the holding finger 106 and the sweep arm 106^a likewise suddenly move to the left and the hooked end and toothed 35 edge of the arm 106 and the plain edge of the arm 106^a engage the two loose yarn ends which project above the top of plate 92 and the yarn holder 103, feeding the short one of said ends toward a chute 130 by the arm 40 106^a and carrying the other end across, by the arm 106, and gripping it against the roughened top surface of the plate 93 where it, with the ends *y* and *z*, is immovably held.

The release by the fingers 199—200 of the 45 tied ends of the yarns *w* and *x* permits the sweep arm 37 of the stop motion to move upwardly to its normal position to take up any slack in said yarn and the knitting machine is now fed by the yarn *x* which has been laid by the carrier segment 44, back 50 of the arm of the latter and against the sleeve 45^a thereof to the back face of the shield 88 as shown in Figs. 15 and 16 to prevent said yarn from entering between the guard plate 101 and the shield 88 where it might engage and draw upwardly with it one or more of the other yarns.

It is to be understood that when the parts 60 occupy the positions indicated in Figs. 15 and 25, the carrier segment 44 begins its return movement in a clockwise direction as the link 86 is drawn down by the action of the eccentric 76 transmitted through rod 77 and the arm 77^a which acts to positively 65 turn the arm 82 with the gear 43 and sleeve

45^a. Such turning of said gear so turns the selector 56 that the previously depressed yarn finger 50 is permitted to move to its upper position under the action of its spring 54.

The turning of the sprocket wheel 19 has now moved the chain 21 sufficiently to cause the roller 27 to pass off of its actuating link 21^b, whereupon the spring 31 turns the lever 30 in a clockwise direction, swinging the controller cam 83 under the pawl 81 so as to prevent further movement of the arm 82, even though the rotation of the eccentric 76 reciprocates the rod 77. At the same time the movement of the cam 63 with the lever 80 30 returns the selector rod 60 toward the right to its extreme position in the plane of the yarn guiding finger 49, where the selector pin 57 maintains the arm 75 in the raised position necessary to hold up the vertical 85 shaft 72 with the arm 73 above the plane of rotation of the cam 74 on the cylinder cam ring 3 and the arm 73^a on said spindle in a position to be engaged by the cam 74^a on said cam ring.

The machine will now knit any required 90 number of courses to form a transverse stripe of definite color on the fabric being knitted, whose width will depend upon the number of low links in the pattern chain 21 before another high link is brought into engagement with the roller 27, as above explained. When this again occurs, the above described cycle of operations is repeated and if it be assumed that the yarn guiding finger 51 is depressed, then the yarn *y* of another color is fed through said finger and will be 95 knotted to the running yarn *x* which has been previously fed through the finger 50 and a differently colored stripe will be 100 105 knitted into the fabric, a fourth color *z* may be added to the yarn *y* in a manner above described.

A fabric may be produced in the above 110 described manner having, in the present instance, four different colors arranged in stripes of any desired width or order of succession depending upon the manner in which the various high and low links of the pattern chain 21 may be assembled.

It is to be noted that when yarn is being 115 fed from the finger 52 at the extreme left hand end of the series and it is desired to change, tie or connect it to some other yarn, the movement of the end of this latter yarn by the carrier segment 44 naturally cannot engage the yarn *z* to draw it from behind the shield 88 to a position between the latter and the guard plate 101, as is required in 120 order that the above operations may be carried out as described. I, therefore, mount on the arm 47 of the carrier segment 44, a projecting tongue 120 which as said segment turns, moves in a circular arc immediately outside of the circularly curved edge 125 130

of the shield 88, and picks up the yarn α from the finger 52, carrying it over the rear face of the shield 88 to the point thereof, where it is free to move into a position immediately back of the guard plate 101. Thereafter the operations proceed as previously described.

In my machine as so far described, the spring-actuated finger 103 for temporarily holding the inactive yarn ends, is moved against the action of its spring by said yarn ends themselves so that the strength of the spring and consequently the holding ability of said finger is limited, but efficient on cotton or woolen yarns. I find, however, that when silk yarn is employed, for which the particular design of snubbing and knotting mechanism above described is adapted, it is necessary to employ a stronger spring than would permit the above method of operation of the finger 103 and I, therefore, provide the construction illustrated in Figs. 4 and 6, for positively moving said finger in one direction. In this preferred form of my device the holding arm 106 has the form illustrated in said figures and includes a projecting lug 150 designed to co-operate with an arm 151 projecting from the temporary yarn holding finger 103. The latter is acted on by a relatively powerful spring 105 to confine yarns between its under surface and the roughened top surface of the plate 93, but is swung outwardly and held in an inactive position by the lug 150 as long as the hooked arm 106 is in position to hold the yarn ends. When, however, said arm is swung to the right, the lug 150 moves away from the arm 151, permitting the finger 103 to swing in under the action of its spring to grip and firmly hold the yarn ends against the face of the shield 88. The return of the hook arm 106 to its normal position acts through the arm 151 to swing the temporary holding finger 103 outwardly.

In operation, I have found the mechanism above described to satisfactorily perform the work for which it was designed, the several parts acting with certainty and requiring a minimum of attention. Obviously, the number of yarn sources and the number of yarn feeding fingers 49, 50, etc., may be made more or less than four without departing from my invention which broadly contemplates the provision of mechanism for automatically connecting one or any number of yarns successively to a yarn or thread while it is being fed to a knitting machine.

My improved knotting mechanism is particularly efficient when it is desired to tie two adjacent silk ends or a silk and a cotton or woolen end. This condition, hitherto considered impractical with automatic means, is obtained by the snubbing action between the fixed and movable blades of the knotting hook which prevents the slipping of

the silk thread such as occurs when the snubbing action is not employed or when a plain frictional contact is used therewith.

The improved snubbing knotter makes possible the use of a cheap low grade of thread in instances where a portion of the knitted fabric is to be raveled and wasted which is necessary in some classes of work such as when making hosiery tops, the foot portion of which is to be formed on another machine.

I claim:

1. In thread delivery mechanism for knitting machines, knot tying mechanism comprising a frame; rigidly constructed blades movably mounted in said frame; movable blades adapted to co-operate with said rigid blades, for knotting said threads; means for moving said blades in unison; and means movable with respect to said frame and said unitary blade moving means, for causing a co-operative movement between said rigid and said movable blades. 80 85

2. In thread delivery mechanism for knitting machines, knot tying mechanism comprising a frame; rigidly constructed blades rotatably mounted in said frame; movable blades adapted to co-operate with said rigid blades, for knotting said threads; means for rotating said blades in unison; and means movable with respect to said frame and said unitary blade rotating means for causing a co-operative movement between said rigid and said movable blades. 90 95

3. In thread delivery mechanism for knitting machines, knot tying mechanism comprising a frame; a knotting hook, comprising rigidly constructed blades and movable blades pivoted to said rigid blades and adapted to co-operate with said rigid blades, for knotting said threads; means for rotating said knotting hook; and means movable with respect to said frame and said hook for causing a co-operative movement between said rigid and said movable blades thereof. 100 105 110

4. In thread delivery mechanism for knitting machines, knot tying mechanism comprising a frame; a knotting hook comprising rigidly constructed blades and movable blades pivoted thereto and adapted to co-operate with said rigid blades, for knotting said threads; means for rotating said knotting hook; and means rotatable in a direction opposite to said hook and with respect to said frame and said hook for causing a co-operative movement between said rigid and said movable blades. 115 120 125

5. In thread delivery mechanism for knitting machines, knot tying mechanism comprising a frame; a knotting hook comprising rigidly constructed blades; and movable blades pivoted thereto and adapted to co-operate with said rigid blades, for knotting said threads; means for rotating said hook; an eccentric ring rotatably mounted in said 130

frame and adapted to be rotated in a direction opposite that of the said hook and with respect to said frame and said hook for causing a co-operative movement between said rigid and said movable blades thereof.

6. In thread delivery mechanism for knitting machines, knot tying mechanism comprising a frame; a knotting hook comprising rigidly constructed snubbing blades and a rigidly constructed shear blade; movable blades adapted to co-operate with said rigid blades, for knotting said threads comprising movable snubbing blades and a movable shear blade; means for rotating said blades in unison and in a definite direction; and an eccentric ring adapted to engage said movable blade and to be rotated with respect to said frame and in a direction opposed to the direction of rotation of said hook, for causing a co-operative movement between said rigid and said movable blades.

7. In thread delivery mechanism for knitting machines, knot tying mechanism comprising a casing; a frame within said casing; a knotting hook comprising rigidly constructed blades and adapted to be rotated in said frame; movable blades pivoted to said rigid blades and adapted to co-operate with said rigid blades, for knotting said threads; a spindle rotatably mounted in said frame to which said rigid blades are secured, and adapted to rotate said blades in unison; gear teeth on said spindle; a plate gear rotatably mounted in said casing and having teeth adapted to engage said spindle gear; an eccentric ring adapted to engage said movable blades; gear teeth on said eccentric ring adapted to engage a second series of gear teeth on said plate gear, at the opposite side of its centre of rotation from that occupied by said spindle gear; and means for rotating said plate gear, whereby the said knotting hook is rotated in one direction and the eccentric ring is rotated in a direction opposite thereto.

8. In thread delivery mechanism for knitting machines, knot tying mechanism comprising a casing; a knotting hook comprising relatively fixed and movable blades, adapted to co-operate for knotting said threads and adapted to be rotated in a definite direction; an eccentric ring adapted to be rotated in an opposite direction and in engagement with said movable blades; a plate gear in said casing co-operatively engaging said knotting hook and said eccentric ring; and means for rotating said plate gear in a direction to cause co-operative action between said normal relatively fixed and movable blades and also in a reverse direction, to restore said elements to their normal inoperative positions.

9. A knot tying unit comprising a casing; a horizontally disposed spindle rotatably mounted in said casing relatively fixed and

movable blades on said spindle, constituting a knotting hook; gripping fingers adapted to move horizontally above said hook, from a point adjacent one side thereof to a point adjacent the other side thereof; means for co-operatively rotating said hook and horizontally moving said gripping fingers, whereby the adjacent ends of a pair of threads may be gripped by the fingers and by the knotting hook, the hook being turned to tie a knot in the threads and the fingers moving horizontally to draw the knot off the hook; and an eccentric ring adapted to be rotated in a direction opposite to that of the hook, for causing the movable blades of the hook to successively grip and release the ends of the threads while the gripping fingers are moving across the vertical plane of the hook.

10. A knot tying unit comprising a casing; a bearing frame in said casing; a spindle horizontally disposed in said frame; relatively fixed and movable blades on said spindle and constituting a knotting hook; a gear on said spindle; an eccentric ring on said frame and engaging said movable blades; a gear on said eccentric ring; a plate gear in said casing and engaging said spindle gear and said eccentric ring gear, for causing a relative and co-operative movement between said movable blades and said fixed blades.

11. A knot tying unit comprising a casing; a bearing frame in said casing; a knotting hook comprising a spindle horizontally and rotatably mounted in said frame; an eccentric ring rotatably mounted in said frame and axially aligned with said horizontal spindle; a gear on said spindle; a gear on said eccentric ring; a plate gear having teeth meshing with said spindle gear and teeth meshing with said eccentric ring gear; a spindle disposed in said frame in a vertical plane including the centre of rotation of said horizontal spindle; an aperture in said vertical spindle of sufficient proportions to permit vertical rotation of the horizontal spindle therein, and horizontal oscillation of the vertical spindle around the horizontal spindle.

12. In thread knotting mechanism, a knotting hook comprising a series of blades divided into two co-operating groups, of which at least one is relatively movable with respect to the other, each group comprising at least two spaced blades, the blades of one group lying opposite the spaces between the plates of the other group, whereby a silk thread placed between the adjacent edges of said groups of blades will be formed into a plurality of corrugations around said edges when said blades are moved toward each other, for securely holding said silk thread during a knotting operation.

13. In thread knotting mechanism, a knot-

ting hook comprising a series of blades divided into two co-operating groups, of which at least one is relatively movable with respect to the other, each group comprising at least two spaced blades, the blades of one group lying opposite the spaces between the blades of the other group, whereby a silk thread placed between the adjacent edges of said groups of blades will be formed into a plurality of corrugations around said edges

when said blades are moved toward each other, for securely holding said silk thread during a knotting operation, and two adjacent blades at one end of the series positioned one in each of said groups, being respectively provided with co-operating cutting edges for shearing the thread adjacent the knot. 15

WALTER LARKIN.
